UNITED STATES PATENT OFFICE.

HARRY W. ARCHER, OF NEW HAVEN, CONNECTICUT, ASSIGNOR TO THE ACME WIRE CO., OF NEW HAVEN, CONNECTICUT, A CORPORATION.

CORE FOR SPOOLS, REELS, BOBBINS, AND THE LIKE.

Application filed February 15, 1926. Serial No. 88,261.

Fig. 1 is a perspective view of a spool provided with my improved core.

Fig. 2 is a detached perspective view of the core.

5 Fig. 3 is a similar view of a core formed from sheet-metal.

Fig. 4 is a similar view of a sheet-metal core constructed in accordance with my invention and of a type adapted to be clamped 10 upon an arbor.

My invention relates to a core for spools, 15 reels, bobbins and similar articles which are designed to act as holders for such commodities as wire, thread, yarn, cordage, fila-

ments, ribbons, note-sheets, or webs of flexible material. The articles so named may be fundamentally the same with respect to construction and function, the difference being rather a matter of size and the relative pro-

20 portions of their component parts. For convenience of description, I shall use the word "spool" in a broad generic sense to describe the devices listed above and all other devices of kindred nature and use.

25 In marketing certain commodities, such, for example, as insulated electric wire, it has become a well established trade custom to employ a type of spool wherein the coaxial arbor-receiving core-hole is of com-

30 paratively small bore as compared with the outside diameter of the body or barrel-element. This trade requirement of a spool having a small bore and a barrel of large outside diameter has heretofore been met

35 by spool-structures having either thick solid walls of objectionable weight, or complicated skeletonized forms of relatively high cost.

The object of my invention is to provide, 40 at a low cost for manufacture, a simple self-centering core-element of the class described which shall combine rigidity and strength with lightness of weight.

With this general object in view, my invention consists in a core-element characterized by having a substantially-tubular arbor-receiving member provided with longitudinally-disposed spool-supporting vanes.

45 My invention further consists in a core-element having certain details of construction as will be hereinafter described and particularly recited in the claims.

In Figs. 1 and 2 of the drawings, I have shown my invention embodied in a core-element of a type which lends itself most 50 readily to manufacture by moulding or ex-

trusion processes. As shown, the arbor-receiving tube 10 is provided with three-integral longitudinally-disposed radial spool-supporting vanes 11 which are adapted to engage with the interior of a barrel-member 60 12 of a spool-structure, which may be of any approved construction and which includes, as shown, end-flanges 13.

In Fig. 3 of the drawings, I have shown a core formed from a single strip of sheet-metal which is bent to form three tangential spool-supporting vanes 14 and an arbor-receiving tube 15, from which latter the vanes 14 offset.

65 In order to secure the core-element in the spool proper, I prefer to so proportion the radius of the vanes that when the unit is installed within the barrel of a spool, its fit will be sufficiently tight to retain it in place by friction, or the vanes may be caused 70 to slightly embed themselves in the barrel, when the material from which the latter is formed will permit of this.

75 While it may be true that my initially-separate core-element will find its greatest 80 field of usefulness when incorporated in a spool-structure as a permanent part thereof, I also recognize the fact that there are certain conditions which make it desirable to attach the core-element to existing spool-

85 arbors and thereby adapt the arbors to receive spools having bores of a diameter exceeding that of a standard arbor. With this particular requirement in mind, I provide 90 a core such as is shown in Fig. 4. As shown, this core is formed from a single strip of sheet-metal, which is bent to form three radial spool-supporting vanes 16 and an arbor-receiving tube 17, from which the vanes 16 offset.

95 The ends 18 of the strip of metal 19 thus bent are perforated to receive bolts 19 by which the tube 17 may be clamped upon an arbor such as that shown by broken lines in Fig. 4 and designated by the numeral 20. After a core of this type has been 100 clamped upon an arbor, spool-structures may be forced over the vanes and removed therefrom as required.

105 As is obvious from the foregoing description, the material from which my improved core is formed is of but slight importance, since there are great varieties of materials suitable for this purpose. I would have it understood that while I have shown my improved core as provided with three vanes 110

running lengthwise thereof, it is obvious that the vanes may be more or less in number and helically curved if desired.

I claim:

- 5 1. As a new article of manufacture, a skeleton core for spools, reels, and the like, comprising a substantially-tubular arbor-receiving body provided with integral diverging longitudinally-disposed spool-supporting vanes separated one from the other throughout their length by open spaces.
- 10 2. A core for spools, reels and the like, formed from sheet-metal bent to form a substantially-tubular arbor-receiving member and diverging longitudinally-disposed spool-supporting vanes.
- 15 3. A core for spools, reels and the like, formed from sheet-metal bent to form a substantially-tubular arbor-receiving member and diverging longitudinally-disposed spool-supporting vanes.

3. A core for spools, reels and the like, formed from a single strip of sheet material bent to form a substantially-tubular arbor-receiving member and diverging longitudinally-disposed spool-supporting vanes. 20

4. A core for spools, reels and the like, formed from sheet-metal bent to form a substantially-tubular arbor-receiving member and diverging longitudinally-disposed spool-supporting vanes, one of the said vanes being formed in two parts and means for clamping the two parts together, whereby the core may be clamped upon an arbor. 25

In testimony whereof, I have signed this 30 specification.

HARRY W. ARCHER.
